MERCHANDISING DISPLAY STAND FOR WRITING INSTRUMENTS AND THE LIKE

George L. Curran, Atlanta, Ga., assignor to Scripto, Inc., a corporation of Georgia

Filed July 12, 1960, Ser. No. 61,317

Term of patent 14 years

(Cl. D80—9)

Fig. 3

Fig. 1 is a perspective view of the merchandising display stand embodying my new design;

Fig. 2 is a top plan view of the merchandising display stand shown in Fig. 1;

Fig. 3 is a side elevational view thereof; and

Fig. 4 is an enlarged fragmentary, vertical cross-sectional view thereof taken along line 4—4 of Fig. 2, the circular sign being broken away for convenience of illustration.

The dominant features of my design reside in the full-line portions of the drawing.

I claim:

The ornamental design for a merchandising display stand for writing instruments and the like as shown and described.
